(57) **CLAIM**

The ornamental design for a mounting plate, as shown and described.

DESCRIPTION

FIG. 1 is a top front left perspective view of a mounting plate showing the claimed design;

FIG. 2 is a front view thereof;

FIG. 3 is a rear view thereof;

FIG. 4 is a left side view thereof;

FIG. 5 is a right side view thereof;

FIG. 6 is a top view thereof; and

FIG. 7 is a bottom view thereof.

FIG. 8 is a top right perspective view of the mounting plate showing the claimed design in an environment in which it may be used; and,

FIG. 9 is an enlarged view of the mounting plate shown in FIG. 8.

The dash-dot lines depict environmental structure that forms no part of the claimed design. The dot-dash lines in FIGS. 8 and 9 depict the boundaries of the enlarged view and form no part of the claimed design.
